UNITED STATES PATENT OFFICE.

SIMON S. LAUGHLIN, OF COLWICH, KANSAS.

AIR-HEATING SYSTEM.

964,921.

Specification of Letters Patent. Patented July 19, 1910.

Application filed June 30, 1909. Serial No. 505,204.

To all whom it may concern:

Be it known that I, SIMON S. LAUGHLIN, citizen of the United States, residing at Colwich, in the county of Sedgwick and State 5 of Kansas, have invented certain new and useful Improvements in Air-Heating Systems, of which the following is a specification.

This invention relates to heating systems 10 and refers particularly to a system employed in connection with internal combustion engines.

An object of this invention is to utilize 15 the heated air which is passed about the cylinders of an internal combustion engine for heating a car or the like.

The invention has for another object the provision of an improved means whereby the 20 heated air is collected after passing about the cylinders of the engine and conveyed to the desired places to be heated.

A further object of this invention is the provision of an arrangement of air ducts whereby the heated air is carried from the 25 engine and led to the place to be heated, the ducts being provided with dampers or valves for cutting off the heated air to other portions of the ducts when heat is not desired at such portions.

30 The invention has for a still further object the provision of an improved means for conveying air to the cylinders of the internal combustion engine and for passing the air about such cylinders and finally conveying 35 the air, after absorbing the heat from the cylinders to the location to be heated.

For a full understanding of the invention 40 reference is to be had to the following description and accompanying drawings, in which:—

Figure 1 is a side elevation of the improved system as applied to an internal combustion engine, the same being supported in a motor vehicle. Fig. 2 is a top plan view of 45 the same, and Fig. 3 is a sectional fragmentary view of the main duct and one of the loop sections disclosing the valve or damper in a closed position and in dotted lines in an open position.

50 Corresponding and like parts are referred to in the following description and indicated in all the views of the drawing by the same reference characters.

Referring to the drawing the numeral 10 55 designates the base or crank case of an internal combustion engine upon which are

vertically positioned in longitudinal alignment a plurality of cylinders 11. Disposed about each of the cylinders 11 are air jackets 12 which are connected at one side to a pipe 60 13 longitudinally disposed at one side of the jackets 12 and communicated at its forward extremity with a cylindrical casing 14. The pipe 13 is connected to the upper end of the cylindrical casing 14 and receives air 65 therefrom which is forced into the pipe 13 by the provision of a centrifugal fan located within the casing 14 upon the crank shaft 15 of the engine. In the drawings is disclosed the fan as being mounted upon the 70 crank shaft 15, although intermediate shafts or gearing may be employed which are connected to the crank shaft 15 to propel the fan. The fan comprises a pair of spaced rims 16 between which are engaged a plurality of radially extended plates 17 mounted upon a suitable hub 18 keyed to the shaft 15 which receives air from the central forward face of the cylindrical casing 14 which is provided with an opening 19 for the same. 75 Upon the opposite side of the jackets 12 a second pipe 20 is secured which is communicated with each of the jackets 12 and extended backwardly where it terminates in an air duct 21 disclosed as being longitudinally positioned at one side of a motor vehicle and beneath the floor of the same. At intervals throughout the length of the air duct 21 looped sections are formed, which in the application of the device to a motor vehicle as is disclosed in the drawings, are preferably two in number, the looped sections each comprising a pipe which extends 80 upwardly from the air duct 21 as at 22 where it is turned inwardly and horizontally to the desired width and is then turned 85 downwardly to an elbow 23 to dispose the lower horizontal section 24 in a plane advanced from the upwardly curved section 22, which horizontal section 24 terminates 90 in the side of the air duct 21.

100 Located within the air duct 21 is a damper or valve 25 hinged to the upper portion of the duct 21 in such position as to admit of the engagement of the valve 25 against the opening into the section 22 to close the same at times. The valve 25 is mounted upon a stem 26 which extends outwardly to a convenient location upon the side of the car as is disclosed in the drawing, where it is turned at substantially right angles to form 105 a resilient arm 27 for engagement against 110

the serrated face of a segment 28 to frictionally retain the valve 25 in a desired position to admit of various quantities of air into the looped sections.

- 5 In the drawing the looped sections are shown as being located forwardly of the seats of the vehicle, one being located at the rear end of the hood while the second one is positioned at the back of the operator's seat. The duct 21 is extended to the rear end of the vehicle where it is curved upwardly as at 29 to terminate centrally in one edge of a radiator 30 positioned at the back of the vehicle. The discharge casing 30 10 comprises a hollow rectangular chamber having the rear wall thereof perforated to admit of the escape of the air conveyed thereto without exerting a pressure upon the same and also for the purpose of partially overcoming the suction of the car caused by the traveling of the same and the drawing inwardly of the air about the sides thereof.
- 15 In operation when the engine is set in motion the centrifugal fan is operated and a quantity of air is drawn in through the opening 19 and discharged from the cylindrical casing 14 into the pipe 13 where the air is led into the jackets 12 and is caused 20 to absorb the air from the cylinders 11. From the jackets 12 the air is passed through the pipe 20 backwardly into the duct 21 and finally to the discharge casing 30. When it is desired to heat a portion of the car by 25 admitting the heated air to the looped sections the corresponding valve 25 is located to be swung downwardly and to close the duct 21 and to thereby force the heated air into the sections 22, 23 and 24 back into the 30 duct 21 at a point in advance of the valve 25. By this arrangement it is readily observed that the heated air will be forced through the looped sections and caused to heat the same, the radiation from which will 35 raise the temperature about such looped sections. When it is not desired to heat the car the valves 25 are closed and retained in such position by the spring action of the arms 27 against the segments 28 thereby 40 admitting of the direct passage of the heated air from the pipe 20 through the duct 21 to the discharge casing.
- 45 Having thus described the invention what is claimed as new is:—

- 50 1. In combination with an internal com-

bustion engine disposed in the forward end of a motor vehicle, of a plurality of jackets disposed about the cylinders of said engine, means for conveying air to said jackets under pressure, an air duct led from said jackets, a plurality of looped sections communicating at their opposite ends at intervals with said duct, a discharge casing communicating with the extremity of said duct, and positioned at the rear of the vehicle, said discharge casing having a plurality of outlet openings therein, and valves located at the intersections of said looped sections with said duct.

2. In combination with a vehicle and an internal combustion engine mounted in the forward end thereof, of a plurality of jackets disposed about the cylinders of said engine, means for introducing air into said jackets, an air duct connected to all of said jackets, looped sections communicating at intervals with said duct, a discharge casing positioned across the back of said vehicle and communicating with said duct, said discharge casing having a plurality of openings in the rear wall thereof to admit of the escape of heated air therefrom, and valves located in said duct at the intersections of said looped sections to direct heated air to the same at times.

3. In combination with a vehicle, a dashboard on said vehicle, seats transversely located on said vehicle and an internal combustion engine disposed in the forward end of said vehicle, of jackets mounted about said engine, means for introducing air into said jackets, an air duct extended from said jackets and positioned longitudinally beneath said vehicle, pipes forming looped sections communicating with said duct and positioned against said dashboard and the backs of said seats, valves disposed in said ducts to control the entrances to said looped sections, and a discharge casing mounted across the rear of said vehicle and communicating with said duct, said casing having a plurality of openings therein for the escape of the heated air from said duct.

In testimony whereof I affix my signature in presence of two witnesses.

SIMON S. LAUGHLIN. [L. s.]
